US00D735832S

(12) **United States Design Patent**
Fitzpatrick et al.

(10) **Patent No.:** US D735,832 S
(45) **Date of Patent:** ** Aug. 4, 2015

(54) **FIREARM GRIP**

(71) Applicant: **Magpul Industries Corp.**, Boulder, CO (US)

(72) Inventors: **Richard M. Fitzpatrick**, Longmont, CO (US); **Michael T. Mayberry**, Denver, CO (US); **Thomas Ward**, Tualatin, OR (US)

(73) Assignee: **MAGPUL INDUSTRIES CORP.**, Boulder, CO (US)

(**) Term: **14 Years**

(21) Appl. No.: **29/478,938**

(22) Filed: **Jan. 9, 2014**

(51) LOC (10) Cl. 22-01

(52) U.S. Cl.

USPC **D22/108**

(58) **Field of Classification Search**

USPC D22/108; 362/109-114; 42/90, 94, 114,

(57) **CLAIM**

The ornamental design for a firearm grip, as shown and described.

DESCRIPTION

FIG. 1 is a left, top, rear perspective view of a firearm grip showing our new design;

FIG. 2 is a front elevation view of the firearm grip of FIG. 1; FIG. 3 is a rear elevation view of the firearm grip of FIG. 1; FIG. 4 is a left side elevation view of the firearm grip of FIG. 1;

FIG. 5 is a right side elevation view of the firearm grip of FIG. 1;

FIG. 6 is a top plan view of the firearm grip of FIG. 1;

FIG. 7 is a bottom plan view of the firearm grip of FIG. 1; FIG. 8 is a left, top, rear perspective view of a firearm grip showing our new design;

FIG. 9 is a front elevation view of the firearm grip of FIG. 8; FIG. 10 is a rear elevation view of the firearm grip of FIG. 8; FIG. 11 is a left side elevation view of the firearm grip of FIG. 8;

FIG. 12 is a right side elevation view of the firearm grip of FIG. 8;

FIG. 13 is a top plan view of the firearm grip of FIG. 8; FIG. 14 is a bottom plan view of the firearm grip of FIG. 8; and,

FIG. 15 is a right, top, front perspective view of a firearm grip coupled to a firearm showing our new design.

The broken lines showing portions of the design in all figures are included for the purpose of illustrating environment and unclaimed features and forms no part of the claimed design.

1 Claim, 15 Drawing Sheets
